US0D1040780S

(12) **United States Design Patent** (10) Patent No.: **US D1,040,780 S**
Chen (45) Date of Patent: ** Sep. 3, 2024

(54) **STAND**

(71) Applicant: **Meteor City LLC**, Wilmington, DE (US)

(72) Inventor: **Brian Johnny Chen**, Wilmington, DE (US)

(73) Assignee: **METEOR CITY LLC**, Wilmington, DE (US)

(**) Term: **15 Years**

(21) Appl. No.: **29/869,096**

(22) Filed: **Dec. 21, 2022**

(51) LOC (14) Cl. **14-03**

(52) U.S. Cl.

USPC **D14/217**

(57) **CLAIM**

The ornamental design for a stand, as shown and described.

DESCRIPTION

FIG. 1 is a perspective view of a stand showing a new design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The broken lines illustrate portions of the stand that form no part of the claimed design.

1 Claim, 7 Drawing Sheets
